UNITED STATES PATENT OFFICE.

JOHN MCGRANIGHAN, OF ROXBOROUGH, PENNSYLVANIA.

COIN-CONTROLLED DISPENSING APPARATUS.

Application filed May 8, 1922. Serial No. 559,132.

This invention is an improved apparatus whereby an oscillatory handle is adapted to be connected with an oscillatory valve by means of a coin so that the handle will act 5 through the coin to open the valve and dispense air for filling automobile tires; the handle being reversed manually or automatically first to release the coin and then to close the valve without the intervention of 10 such coin.

The characteristic features of my improved apparatus are set out in the accompanying drawings in illustration thereof.

In the drawings, Fig. 1 is a broken top 15 plan view of a coin controlled apparatus embodying my improvements; Fig. 2 is a sectional view taken on the line 2^x—2^x of Fig. 1; Fig. 3 is a broken side elevational and irregular sectional view of the same, and Fig. 20 4 is a sectional view of details in illustration of different positions of the coin and the parts connected thereby in the movement of operating the valve.

The apparatus, as illustrated in the drawings, is applied to a fluid conduit 1 containing a valve 2 adapted to be operated by a stem 3. A closed box or case 4 is fixed to the conduit 1 (preferably centrally with reference to the valve 2) by the brackets or 30 bearings 5. The box has in the bottom thereof a door 6 adapted to turn on a hinge 7 and to be secured in closed position by the engagement of its hasp 8 with the staple 9 on a side of the box, and the action of a lock 10 fixed to the staple so as to hold the hasp thereon.

A shank 11, preferably consisting of a hollow tube, is fixed on the end of the valve stem 3, and a rod 12 extends into the tube 11, the tube and rod passing through and turning in the respective openings 13 and 14 in the sides of the box. The rod is provided with a pin or stud 15 which is movable in a circular slot 16 formed in the tube, the rod thus having a limited oscillatory movement relative to the tube and is adapted to turn the same. The tube 11 is provided with the diametrically disposed slots 17 extending longitudinally thereof and the rod 12 is 50 provided with the slot 18 adapted to register

with the slots in the tube, these slots in their registering vertical position having in line therewith a slot 19 in the otherwise closed top of the box.

A yoke 20 is fixed by a frame 21 within 55 the box beneath the slots 17, 18 and 19, so that when a coin 22 is dropped through the slot 19 and into the registering slots 17 and 18 in line therewith, such coin will fall into engagement with the yoke 20 and be held 60 thereby partially within the slot 18 so as to lock the parts 11 and 12 together.

A handle 23 on the rod 12 occupies an approximately vertical position when the slots 17, 18 and 19 register. When turned 65 anti-clockwise from the vertical position through approximately 90° and into engagement with the stop 24 fixed to a side of the box, the handle acts through the parts 12 and 11 connected by the coin 22 to open the valve 70 2 and permit the flow of air therethrough, from a source of supply to a tire.

Upon dispensing the amount of fluid desired, as in drawing sufficient air to fill a tire tube, the handle 23 is turned clockwise, with 75 the result that the coin 22 is released and drops clear of the yoke 20 to the bottom of the case. Thereafter the stud 15 engages the end of the slot 16, turns the tube 11 together with the stem 3 and closes the valve 2, the 80 handle 23 engaging the lug 25 of the top of the box when it reaches the vertical position corresponding to the closed position of the valve.

It will be understood that this closing operation can be effected by elevating the handle 23 from the approximately horizontal to the approximately vertical position manually, or the closure can be effected automatically by means of a coiled spring 26 having 90 one end fixed to an anchor 27 and the other end to the stud 28.

Having described my invention, I claim:—

The combination with a rotary valve, of control mechanism therefor comprising relatively revolute members consisting of a shaft having a rod therein, one of said members being connected with said rotary valve and the other of said members having a handle connected therewith, said members hav- 95 100

ing a coin slot extending diametrically entirely therethrough, a coin support below said slot and relatively to which said members are revolute to remove a coin from said support, and a pin and slot connection between said revolute members whereby one of said members is movable by the other

upon the operation of said handle in one direction and said last named member is movable independently of the other by the movement of the handle in the opposite direction. ¹⁰

In testimony whereof I have hereunto set my name this 24th day of April, 1922.

JOHN McGRANIGHAN.
